UNITED STATES PATENT OFFICE.

SYLVESTER JOSEPH MOORE, OF LONDON, ONTARIO, CANADA, ASSIGNOR OF ONE-HALF
TO JOHN SYLVESTER MOORE, OF LONDON, CANADA.

GAS-METER.

1,272,499.

Specification of Letters Patent.

Patented July 16, 1918.

Application filed February 14, 1918. Serial No. 217,231.

To all whom it may concern:

Be it known that I, SYLVESTER JOSEPH MOORE, of the city of London, in the county of Middlesex, Province of Ontario, Dominion of Canada, a subject of the King of Great Britain, have invented certain new and useful Improvements in Gas-Meters, of which the following is a specification.

This invention relates to improvements in the ordinary type of dry gas meter in which the gas chambers or bellows are formed with movable diaphragms, which actuate the flag wires which move, through suitable connections, the valves and registering mechanism, and my object is to devise means for increasing the capacity of the meter without materially increasing the dimensions of the meter or increasing the rate of operation of the mechanism operating the valves and registering mechanism.

I attain my object by providing for a greater range of movement than usual for the diaphragms and by connecting said diaphragms with the flag wires by compound lever systems which permit of the greater movement of the diaphragms without increasing the angular movement of the flag wires.

The invention is hereinafter more specifically described and illustrated in the accompanying drawings in which—

Figure 1 is a plan view, partly broken away, of parts of a meter constructed in accordance with my invention;

Fig. 2 a front elevation, partly broken away, showing the same parts;

Fig. 3 a front elevation illustrating a modification of the compound lever through the medium of which one of the diaphragms actuates the flag wire; and

Fig. 4 a plan view, partly in section of the compound lever system shown in Fig. 3.

In the drawings like numerals of reference indicate corresponding parts in the different figures.

The gas meter is of ordinary type in every respect save for the connections between the flag wires and the diaphragms, and only such portions of the meter are herein described and illustrated in the drawings as are necessary to a proper understanding of the mode of operation of the improved construction.

1 are the flag wires to which are connected the rock arms 2 which, by means of links

3, are connected to the crank 4 of the crank shaft 5. From this crank shaft the valves and registering device are operated in the usual manner. The valves and registering device, not forming part of the present invention, are omitted to permit of the better showing of the parts more directly associated with the improved constructions.

The diaphragms 6, as usual, form the ends of bellows of which 7 are the usual annular leather sides. These diaphragms are provided with the usual guiding rock arms 8 secured to the rock shaft 9 journaled in suitable bearings on the bottom of the casing of the meter. To each flag wire is connected 70 a lever arm 10, which extends well past the center of the diaphragm and can therefore be made considerably longer than the ordinary lever arm which extends from the flag wire to the center of the diaphragm. 75

A second lever arm 11 is fulcrumed on the casing, preferably by being secured to a rock shaft 12 journaled in bearings secured to the end of the casing opposite the flag wire. The lever arm 11, in the preferred construction shown in Figs. 1 and 2, thus rocks on an axis substantially parallel to the axis of flag wire lever arm 10. The flag wire lever arm 10 has a sliding and rocking connection with the lever arm 11 between the ends of the latter. 80

The preferable arrangement is shown in Figs. 1 and 2 in which a member 13 has its ends pivoted in brackets 14 secured to the lever arm 11, which is preferably double as 90 shown. In the member 13 is formed a hole through which the flag wire lever arm 10 is adapted to slide. The lever arm 11 thus maintains its operating connection with the flag wire lever arm 10 notwithstanding the 95 constant changes in the relative position of the two lever arms as the diaphragm travels in and out.

While the construction shown in Figs. 1 and 2 is preferred, other arrangements are 100 possible. For instance, in Fig. 3 the second lever arm 11 is shown extending at right angles to the flag wire lever arm 10, which latter is shown as extending through a slot formed lengthwise of the lever arm 11. 105

By adopting a compound lever system as illustrated as the operating connection between each diaphragm and its corresponding flag wire, the length of travel of each diaphragm may be materially increased 110

without rocking the flag wire lever arm through a substantially greater arc than is now commonly the case. Consequently there is no greater movement of the flag wire and the parts actuated thereby. A meter of greater capacity is thus obtained without any greater wear and tear on the valves or parts actuating the registering mechanism. Outside the special constructions described, the only changes required in the meter will be to construct the annular leather sides so as to provide for the greater movement of the diaphragms and to suitably calibrate the registering mechanism.

What I claim as my invention is:

1. In a meter provided with movable diaphragms operating flag wires, which by suitable rock arm and linkage systems actuate the valves and registering mechanism, a compound lever system between each flag wire and its corresponding diaphragm comprising a lever arm connected to the flag wire; a lever arm pivotally connected to the diaphragm; and a stationary part on

which the lever arm is fulcrumed, said lever arms having a rocking and sliding engagement the one with the other.

2. A specific construction of the device set forth in claim 1 in which the second lever arm is arranged to rock on an axis parallel to the axis of the flag wire lever arm and is fulcrumed at the opposite end of the meter and the connection between the two lever arms comprises a member pivotally connected to one lever arm and through which the other arm slides.

3. A specific construction of the lever system set forth in claims 1 and 2 in which the second lever arm is double and the connecting member through which the flag wire lever arm slides is pivoted to each part of the arm.

Signed at London this 24th day of January, 1918.

SYLVESTER JOSEPH MOORE.
